(57) **CLAIM**

The ornamental design for a spray container, as shown and described.

DESCRIPTION

FIG. 1 is a front perspective view of a spray container.

FIG. 2 is a rear perspective view thereof.

FIG. 3 is a front view thereof.

FIG. 4 is a rear view thereof.

FIG. 5 is a top plan view thereof.

FIG. 6 is a bottom plan view thereof.

FIG. 7 is a right side view thereof.

FIG. 8 is a left side view thereof.

FIG. 9 is an enlarged sectional view taken along the line 9-9 in FIG. 5 with the unclaimed bottle portion partially removed for ease of illustration.

FIG. 10 is a reference front perspective view showing the unlocked state thereof; and,

FIG. 11 is a reference rear perspective view showing the unlocked state thereof.

The broken lines show portions of a spray container that form no part of the claimed design.

The alternate long and short dash lines are merely the boundary lines between the claimed portions and the non-claimed portions.
